OIL COOLER

Robert A. Richter, United States Navy

Application October 25, 1945, Serial No. 624,627

5 Claims. (Cl. 257—128)

(Granted under the act of March 3, 1883, as
amended April 30, 1928; 370 O. G. 757)

1

The present invention relates to an oil cooler and particularly to tubes in the cooler.

An object of the present invention is the provision of means for eliminating vibration fatigue of tubes.

Another object of the present invention is the provision of means compensating for heat expansion and contraction of tubes in the cooler.

A still further object of the present invention is the provision of means that permits the ready removal of a defective tube from a cooler.

Other objects and advantages of the invention will become apparent as the description proceeds and is taken in connection with the accompanying drawings wherein like characters of reference designate corresponding parts throughout the several views, and wherein:

Fig. 1 is an end-elevational view of an oil cooler and illustrating the nesting of the tubes therein.

Fig. 2 is a view taken on line 2—2 of Fig. 1 looking in the direction of the arrows, and showing flanges with openings and apertures.

Fig. 3 is a view taken on line 3—3 of Fig. 1 and looking in the direction of the arrows.

Fig. 4 is a top plan view of a gasket.

Fig. 5 is a transverse, fragmentary view taken on line 5—5 of Fig. 1.

Fig. 6 is an enlarged end view of tubes and illustrating the nesting of the tubes on the inner peripheral wall of a cooler housing, the housing being shown fragmentarily.

Fig. 7 is a side elevational view of one form of a tube end, the end of the tube being shown in detail in end elevation, the tube being shown fragmentarily.

Fig. 8 is a side elevational view of another form of a tube, the end of the tube being shown in detail in end elevation, the tube being shown fragmentarily.

Fig. 9 is a partial sectional view of the upper semi-circular element and the thermostatic valve fitting connected thereto, taken substantially on the line 9—9 of Fig. 2.

Referring to the drawings, the numeral 10 represents a casing that comprises two semi-circular elements 11 and 12, the element 11 being provided with a channel 13, flanges 14 and apertures 15, the channel 13 having an outlet 16 in the flanges 14, the inner peripheral wall 11 being provided with resilient strips 17. Centrally of the element 11 there is provided in the inner peripheral wall elongated openings 18, 19 and 20 that are in communication with the channel 13.

The element 12 is provided with a channel 21, flanges 22 and apertures 23; the channel 21 having

an outlet 24 in the flanges 22, the inner peripheral wall 12 being provided with resilient strips 25. Centrally of the element 12 there is provided an outlet port 26, an inlet port 27 and a decongealing tube 28. Interposed between the elements 11 and 12 as shown in Figs. 1 and 4 are gaskets 29 having an elongated opening 30 and apertures 31, the openings 30 being in alignment with the outlets 16 and 24, the apertures 31 being in alignment with the apertures 15 and 23. As shown in Fig. 1 the elements 11 and 12 are fixedly secured by bolts 32 and nuts 33.

Within the casing 10 there is mounted a plurality of tubes 34 and 35, illustrated in Fig. 1, the tubes 34 having an end portion 36 that is of hexangular configuration shown in end elevation in Fig. 7 and being covered with a resilient rubber substance 37, forming a cushioning means. In Fig. 8 the tubes 35 have an end portion 38 that is of substantially quadrilateral configuration as shown in end elevation in Fig. 8 and being covered with a resilient rubber substance 39, forming a cushioning means, the wall 40 being of arcuate configuration to conform to the arc of the inner peripheral walls of elements 11 and 12. The ends 36 and 38 of the tubes 34 and 35 being larger than the diameter of the tubes provide a uniform spacing of the tubes in the casing 10.

In the assembling of the tubes in the housing as shown in Fig. 6 a tube 35 is placed in the housing 10 the wall 40 engaging the resilient strips 17. Next one of the tubes 34 is placed in the housing 10, the wall 41 of the end portion 36 engaging the wall 42 of the end portion 38. On the opposite side of the end portion 36 is placed another tube 35 the end wall 43 engaging the wall 44 of the end portion 36, the arcuate portions 45 engaging the resilient strip 17. Tubes are inserted into the casing until the entire inner area of the elements 11 and 12 are filled, and at this point the nuts 33 are tightened and the elements brought together. During the tightening of the bolts the ends of the tubes are squeezed together certain portions of some of the tube ends engaging the resilient strips 17 and 25, thus providing leak proof end walls for the cooler. The tubes 34 and 35 in assembled position are in spaced relation and allow oil passing through the channels 13 and 21 into the openings 18, 19 and 20 to pass around the tubes 34 and 35 to the outlet port 26. From the description of the arrangement of parts it can be seen that if one of the tubes 34 or 35 should go bad, it is a simple matter to replace the tube by simply loos-

ening the nuts 33 enough to pull the bad tube out, replace it with a new one, then tighten up the nuts 33.

The decongealing tube 28 is substantially rectangular in section and extends down through the casing nearly to the bottom of the core. The adjacent tubes 34 and 35 may be spread apart to pass around it by slightly bending their central portions outwardly. At the top this tube is connected by a funnel shaped passage 46 through the casing to the port 47 controlled by a thermostatic valve 48 which is connected by rectangular passage 49 in fitting 50, to which the outlet 26 is also directly connected, to a discharge conduit from the cooler back to the engine. The thermostatic valve fitting 50 forms no part of the present invention and is disclosed merely to clarify the operation of the present oil cooler.

The hot oil from the engine enters the oil cooler through inlet 27 and thence flows around the channel 13 to and through the openings 18, 19 and 20. If the lubricant within the radiator is congealed to such an extent that the resistance to flow through the radiator between the tubes is greater than the resistance to flow through the decongealing tube 28, the lubricant will take the course of least resistance and flow through the decongealing tube 28. Thence the oil will flow through passage 46, port 47, passage 49, and finally to a discharge conduit and back to the engine. The thermostatic valve 48 is normally full open, but starts to close as the radiator becomes warmed-up and the temperature of the oil increases. When outlet port 47 is fully closed by thermostatic valve 48, all hot oil is forced through the radiator (between the tubes) and out through outlet 26, passage 47, and thence back to the engine. Just before the outlet port 47 is fully closed by valve 48, hot oil from the engine enters the discharge conduit back to the engine both from the decongealing tube and from core outlet 26.

The invention described herein may be manufactured and used by or for the Government of the United States of America for governmental purposes without the payment of any royalties thereon or therefor.

What I claim is:

1. A cooler for congealable liquid, comprising: a pair of semi-cylindrical jacket members, one member being provided with an inlet through the outer jacket wall and two outlet passages through the jacket chamber and jacket walls, and the other member being provided with an opening through its inner jacket wall; matching flanges on said members disposed in face to face relation, the flanges having passages therethrough in registry with the jacket chambers and in registry with each other; elastic sealing means interposed between the flanges, said sealing means being provided with passages in registry with the passages in said flanges; a stack of tubes in the space defined by said members, said tubes extending parallel to the axis of said members; individual elastic sleeves on the ends of said tubes, said sleeves having a plurality of working faces on the external periphery thereof arranged to coact with working faces on adjacent sleeves or with the adjacent inner periphery of said elements; a decongealing tube connected to one of said outlet passages and extending approximately to said opening in said other member; and means for locking the semi-circular elements together, through means of their flanges, operative to form a fluidtight seal between said working surfaces when compressed.

2. The apparatus of claim 1 and a discharge conduit connected to the decongealing tube outlet; and a thermostatic valve in said conduit for controlling said decongealing tube outlet.

3. A cooler for congealable liquid, comprising: intake and discharge conduit means; a pair of semi-cylindrical jacket members, one member being provided with an inlet through the outer jacket wall and two outlet passages through the jacket chamber and jacket walls, said inlet being connected to said intake conduit means, said outlet passages being operatively connected to said discharge conduit means, and the other member being provided with an opening through its inner jacket wall; matching flanges on said members disposed in face to face relation, the flanges having passages therethrough in registry with the jacket chambers and in registry with each other; elastic sealing means interposed between the flanges, said sealing means being provided with passages in registry with the passages in said flanges; a stack of tubes in the space defined by said members, said tubes extending parallel to the axis of said members; individual elastic sleeves on the ends of said tubes, said sleeves having a plurality of working faces on the external periphery thereof arranged to coact with working faces on adjacent sleeves or with the adjacent inner periphery of said elements; a decongealing tube connected to one of said outlet passages and extending approximately to said opening in said other member; and means for locking the semi-circular elements together, through means of their flanges, operative to form a fluidtight seal between said working surfaces when compressed.

4. A cooler for congealable liquid, comprising: intake and discharge conduit means; a pair of semi-cylindrical jacket members, one member being provided with an inlet through the outer jacket wall and two outlet passages through the jacket chamber and jacket walls, said inlet being connected to said intake conduit means, and the other member being provided with an opening through its inner jacket wall; matching flanges on said members disposed in face to face relation, the flanges having passages therethrough in registry with the jacket chambers and in registry with each other; elastic sealing means interposed between the flanges, said sealing means being provided with passages in registry with the passages in said flanges; a stack of tubes in the space defined by said members, said tubes extending parallel to the axis of said members; individual elastic sleeves on the ends of said tubes, said sleeves having a plurality of working faces on the external periphery thereof arranged to coact with working faces on adjacent sleeves or with the adjacent inner periphery of said elements; a decongealing tube connected to one of said outlet passages and extending approximately to said opening in said other member; and means for locking the semi-circular elements together, through means of their flanges, operative to form a fluidtight seal between said working surfaces when compressed; and thermostatic valve means operatively connected to said one member for controlling said decongealing tube outlet passage to said discharge conduit means.

5. A cooler for congealable liquid, comprising: intake and discharge conduit means; a pair of semi-cylindrical jacket members, one member being provided with an inlet through the outer jacket wall and two outlet passages through the jacket chamber and jacket walls, said inlet be-

ing connected to said intake conduit means, and the other member being provided with an opening through its inner jacket wall; matching flanges on said members disposed in face to face relation, the flanges having passages therethrough in registry with the jacket chambers and in registry with each other; elastic sealing means interposed between the flanges, said sealing means being provided with passages in registry with the passages in said flanges; a stack of tubes in the space defined by said members, said tubes extending parallel to the axis of said members; individual elastic sleeves on the ends of said tubes, said sleeves having a plurality of working faces on the external periphery thereof arranged to coact with working faces on adjacent sleeves or with the adjacent inner periphery of said elements; a decongealing tube connected to one of said outlet passages and extending approximately to said opening in said other member; means for locking the semi-circular elements together, through means of their flanges, operative to form a fluidtight seal between said working surfaces when compressed; and thermostatic valve means

5 operatively connected to said one member and interposed between said two outlet passages and said discharge conduit means for connecting said outlet passages to said discharge conduit means selectively in accordance with variations in the temperature of the liquid.
